UNITED STATES PATENT OFFICE.

FREDERIC W. C. SCHNIEWIND, OF NEW YORK, N. Y.

COKE-OVEN-DISCHARGING APPARATUS.

976,934.

Specification of Letters Patent. Patented Nov. 29, 1910.

Application filed October 24, 1907, Serial No. 398,901. Renewed October 22, 1910. Serial No. 588,539.

To all whom it may concern:

Be it known that I, FREDERIC W. C. SCHNIEWIND, a citizen of the United States of America, residing in the city, county, and State of New York, have invented a certain new and useful Improvement in Coke-Oven-Discharging Apparatus, of which the following is a true and exact description, reference being had to the accompanying drawings, which form a part thereof.

The present invention relates to apparatus for removing coke from the retorts or coking chambers of coke oven structures, and for receiving and discharging the coke removed from the retorts to a receiving station, where the coke is discharged either into cars for railway transportation or into other storing devices.

The object of the present invention is to provide apparatus so constructed and arranged that the coke from each retort can be readily and easily transferred to a suitable coke receiver without undue jarring of the coke and in a gradual manner so that the coke will neither jam in the retort being emptied or be broken up, thus avoiding injury to the oven walls and undue crumbling of the coke, with a consequent material reduction in the amount of coke "breeze" or waste coke dust formed.

Another object of the invention is the provision of means by which the coke may be covered during the discharging operation and during the transportation of the coke to the discharge station by a movable cover or lid.

The apparatus disclosed is particularly designed for discharging coke ovens in which the ovens proper are emptied through their lower ends. In this form of the invention, the cover or lid is formed or carried by a carriage movable on a level above that on which the coke receiver runs, and serves to cover the hot coke and protect the oven structure from the heat of the coke on the receiver.

A further object of the invention is to so arrange the instrumentalities employed that they may be properly coördinated in their operation and require a minimum of manual attendance.

The invention also has for its object the provision of novel features of construction

and arrangement of the various instrumentalities which will insure good mechanical structures and ease and reliability of operation.

In the claims annexed to and forming a part of this specification it has been aimed to point out with particularity the various features of novelty which characterize the invention. For a better understanding of the invention, however, and the advantages possessed by it, reference may be had to the accompanying drawings and descriptive matter in which I have illustrated and described forms in which the invention may be embodied.

Of the drawings, Figure 1 is a sectional elevation taken parallel to one of the sides of the coke oven structure or battery of ovens, and showing a portion only of the oven structure. Fig. 2 is a section taken at right angles to Fig. 1, but on a larger scale, and also showing a portion only of the coke oven structure. Fig. 3 is an end elevation of the lower portion of the oven structure, illustrating the discharge of the coke from the coke receiver of the discharging apparatus into a railway car located on one of the pair of railroad tracks at opposite sides of the coke receiver. Fig. 4 is a sectional elevation taken similarly to and showing a part of the apparatus shown by Fig. 1, the apparatus shown being modified somewhat from that shown in Fig. 1. Fig. 5 is an elevation, partly in section, of a portion of the coke receiver carriage, illustrating the devices which may be employed for positioning the carriage with respect to the oven structure. Fig. 6 is a view taken at right angles to Fig. 5. Fig. 7 is a diagrammatic elevation of the coke receiver.

In the apparatus shown by the drawings, A represents the masonry walls of the oven proper, which are supported in any suitable manner, as by means of the floor beams A² carried by the main side beams A³, the latter being supported by or rather forming a part of the structural metal understructure A⁴. In the masonry walls are formed a plurality of horizontal elongated and deep vertical retorts A'. By preference, the retorts A' are heated by straight vertical flues A⁵ at the sides of the retorts, and the adjacent flues of adjacent retorts are connected

by passages A⁶ with regenerators A⁷ located between the retorts, burner chambers A⁸ being provided at the upper and lower ends of the flues, all as described and claimed in 6 my copending application Serial No. 398,902 filed of even date herewith, though the present invention is not limited to any special form of heating arrangements.

The bottom wall of each retort is formed 10 by a removable door B, which comprises an upper portion B' of firebrick or tile which normally extends to about the level of the upper edges of the burner chambers A⁸ and is supported by a metal frame B². The 15 metal frame B² is provided at its outer edge with a rib or flange B³ which forms with the body of member B², a sealing trough into which projects the rib C' of a rim member C which extends around the lower 20 end of a retort, and is preferably lined with firebrick C² to shield it and the adjacent floor beams A² from the heat of the glowing coke when the retort is being emptied. The doors or bottom walls B are normally held 25 in place by bolts or rack bars B⁴ operated by pinions B⁵ and engaging ears formed on stiffening yokes B⁶ secured to the members B².

The understructure A⁴ is provided at different levels with rails D', E', and F', on 30 which run the movable lids or coke cover carriages D A and D B, and coke receiver carriage E, and bottom door lift carriage F respectively. The coke receiver carriage E comprises wheels E² running on the rails E' 35 journaled in boxes E³ on which rest the end beams E⁴ supporting the body E⁵ of the carriage E. The wheels E² are driven through gears E⁶ upon cross shafts E⁸ which are in turn driven from the shaft E⁹ 40 of the motor E¹³ secured to the under side of the carriage bottom, the driving connection being formed of pairs of worm wheels E¹⁰ and gear wheel E¹¹ inclosed in casing E¹². On the body portion E⁵ is mounted 45 the coke receiving platform proper G. The platform G is hinge connected to the platform E⁵ at both side edges to tilt relative thereto about one or the other of two axes located one above each rail E'. This arrangement permits coke to be discharged 50 from the receiver into cars located at either side of the carriage on tracks H' as shown in Fig. 3. The hinge connections may be formed by pairs of bearings E¹⁴ formed on the body E⁵, each supporting a shaft or pintle E¹⁵ which is engaged by open ended bearing members G' secured to the under side of the platform G at its opposite side edges. Ears G¹¹ are provided at the side 55 edges of the platform G, those at one edge or the other being engaged by suitable hoisting mechanism located at the end of the battery to tilt the platform about the pintles E¹⁵ at the opposite edge of the platform when it 60 is desired to discharge the coke into the coke

receiving car or other receptacle located at one side or the other of the track rails H', as shown in Fig. 3. The platform G is provided with I-beams G² extending parallel to the track rails E' upon which are removably placed the cast iron plates or bars G³, each provided with the ears G⁵ apertured or grooved to receive the upper flanged edges of a pair of beams G², as shown clearly in Fig. 2. At each end of the platform G is located an inclined and preferably removable end portion G⁶, which comprises inclined beams G⁷ supported at their outer ends on saddle members G⁹ resting on the transverse I-beams G⁸, and having their inner ends directly supported by the body of the platform G. On the rails or beams G⁶ are secured platform bars G³, like those secured on the beams G². The outer ends of the beams G⁶ are faced by end members G¹⁰. 70 80 85

With the construction shown it will be observed that a broken or injured platform bar G³ may be readily removed by sliding out the other bars G³ at one side of it which engage the same pair of beams G² or G⁷. 90 Preferably to facilitate the removal of the bars G² the end portions G⁶ are secured to the body portion of the platform by readily detachable connections, not shown. The carriage E proper may be protected from 95 water employed in quenching by a floor or covering between the platform E and the bars G³ if thought necessary.

The mechanism for dropping and raising each retort door B at the beginning and 100 closing of the retort emptying operation is arranged on the carriage F having wheels running on the track rails F' which may be geared to an operating motor F³. On the platform of the carriage F are located 105 two hoisting devices F⁴ which may both be geared to and operated by the motor F⁵. In the form shown, each hoisting device comprises a conical shell F⁸ in which is mounted a vertically movable hoisting shaft 110 F⁹, having its lower end threaded and carrying at its upper end a head F⁶ adapted to engage the door. The heads F⁶ of the two hoisting devices shown are connected by bars F⁷ which prevent rotation of the shafts F⁹. Within casing F⁸ is located a nut for the corresponding shaft F⁹, the nut having a thrust bearing F¹⁰. Within each casing 115 also is located a worm gear meshing with the teeth formed on the nut F⁹. The worms F¹¹ are carried by the shaft F¹² which may be geared to, or, as shown, may be the shaft of motor F⁵. 120 125

In the construction shown in Figs. 1 and 2 the carriages E and F are entirely independent. As it is desirable however that each door B be dropped to a definite level, viz: that on which the upper edge of the door is flush with the upper ends of the inclined platform portions G⁶, an arrange- 130

ment may be employed with advantage in which the door is dropped down on to the platform E. Such an arrangement is shown in Fig. 4, where the beams E⁴ of the carriage 5 E are extended to form supports on which the door B may be dropped by the hoisting device F⁴. As it is desirable that the carriages E and F should move together during certain stages of the discharging operation 10, an arrangement may be employed for detachably coupling the two carriages together. In the arrangement for this purpose shown in Fig. 4 the carriage E is provided with downwardly extending arms or 15 brackets E¹⁶, which of course should be so arranged as to clear the hoisting mechanism, and the carriage F is provided with similar upwardly extending brackets F¹³, which, when the two carriages are in the position 20 in which they should be coupled together, are located immediately beneath the brackets E¹⁶ so that the two carriages may be secured together by the pin E¹⁷ passing through suitable apertures formed in the brackets 25 E¹⁶ and F¹³.

The means for covering the coke on the platform G and thereby protecting the under oven structure proper from the heat of the coke comprise one or more lids or 30 covers in the form of carriages running on the track rails D'. In the arrangement shown in the drawings there are two of these covers D A and D B employed in discharging each retort. Each of these carriages, which may both be identical in construction, has wheels D² running on the track rails D'. The body of the carriage is provided at its under side with a series of I beams running parallel to the rails D'. 35 The I beams D¹⁴ support plates D³, which may be similar to the platform bars G³, thus forming the lid or cover proper for the glowing coke. To protect the carriages proper against the heat conducted from the 40 faces D³, which are preferably made of cast iron, a suitable non-conducting material like mineral wool may be packed above the faces of the bars D³. To prevent the coke from spilling off the sides of the receiver and also 45 to protect the adjacent portions of the supporting structure A⁴ each side edge of each cover is provided with an apron or depending shield. This apron or shield is formed by metal pieces D⁴ which are provided at 50 their upper ends with grooves receiving the base of the side I beams D¹⁴. For the purpose of connecting carriages D A D B to the carriage E, the body portion of the latter may be provided with posts E¹⁹ arranged 55 in the same vertical planes with posts or brackets D⁵ depending from the sides of the cover carriages. By this arrangement the corresponding posts D⁵ and E¹⁹ may be readily connected as by a pin D⁶ or the like. 60

In discharging each retort A', the car-

riage E is moved in the direction of the arrow shown in Fig. 1 so that the coke is first transferred from the top of the door B to the top of the forward inclined platform G⁶, and is then distributed along the platform G as the movement of the carriage in the direction of the arrow is continued. As the sliding of the platform under the coke is accompanied with considerable friction means must be provided for supporting the coke cake, against the lateral pressure exerted on it. In the form shown in the drawings, the carriages D A and D B are provided at their ends with depending guides D⁷. Adjacent guides D⁷ of the two 75 carriages employed thus unite to form a chute through which the coke passes. With the apparatus operating as shown in Fig. 1, it is of course necessary to hold the left hand cover carriage D A stationary in order to 80 prevent its being displaced by the thrust of the coke as the carriage E moves to the left. The carriage may of course be held stationary in any suitable manner as by locking it to the track rails D' or to the overhead oven 85 beams A². It is also desirable in some cases to regulate the movement of the coke on to the receiving platform. This may be obtained by providing an arrangement whereby by the guides D⁷, may serve in effect as 90 clamping jaws, and be moved relatively to each other in order to clamp and release the coke cake. For the purpose of holding the carriages D A and D B stationary and of adjusting them as desired, as well as for 95 the purpose of obtaining the clamping action referred to between the guides D⁷, the arrangement shown particularly in Figs. 5 and 6 may be employed, although it will be understood that the mechanism shown in 100 105 these figures is merely illustrative of one of many arrangements which may be employed.

In the construction shown best in Figs. 5 and 6, each cover carriage D A or D B is provided at its side between the wheels 110 D² with spur gears D¹⁵ which mesh rack bars D⁸ secured to the overhead oven beams A², and extending parallel to the rails D'. Each spur gear D¹⁵ has a shaft carrying at 115 its inner end a clutch member D⁹ which operates with a clutch member D¹⁰ carried by a shaft D¹¹. The shaft D¹¹ is, by motor D¹³, driven through the spiral gear D¹² carried by the shaft D¹¹ on a worm wheel on the shaft of the motor. 120

When the clutch members D⁹ and D¹⁰ are released, the spur gear D¹⁵ is free to rotate when the carriage D A or D B is moved on the track D' and does not interfere with the movement of the carriage. When, however, the clutch members D⁹ and D¹⁰ are locked together the carriage is effectively locked to the stationary oven structure through the spiral and worm gear connections to the motor D¹³. Such movements of the carriage 130

as is necessary in adjusting the position of the carriage and particularly for obtaining the clamping action between the guides D' of adjacent cover carriages may be obtained 5 by operating motors D¹³. It will of course be understood that the motors D¹³ may be used to propel the carriages D A and D B along the entire length of the track formed by rails D' if desired, but this is not the 10 primary purpose of the motors in the particular construction illustrated, since, the cover carriages may be given large movements by the coke receiver carriage. The clutch members D⁹ and D¹⁰ may be controlled 15 in any suitable manner, for instance, they may unite with suitable electrical connections to form an electro magnetic clutch.

It will be understood that the rails D', E' and F' all extend at least to the end of the 20 battery to which they belong, and that the rails D' extend beyond the battery, and that a suitable quenching apparatus is located beyond the end of the battery for spraying water on the coke and cooling it before dis- 25 charging it from the coke receiver into the cars or other coke receptacles.

Each retort may be discharged as follows: The cover carriages D, the coke receiver carriage E, and the door operating carriage 30 F are all moved to the position shown in Fig. 1. The motor F⁵ is then operated to bring the hoisting heads F⁶ up into engagement with the bottom of the door B. The bolts B⁴ are then withdrawn and the hoisting 35 motor is operated to drop the door to the position shown in Fig. 1. The carriage E and the carriage F are then moved slowly and gradually to the left to allow the coke to descend on to the coke platform G of the carriage E. On account of the gradual upward inclination of the advancing end G⁶ of the receiver platform, the coke cake may be transferred with little or no crumbling from the top of door B to the body of the platform G. Further advancing movement of 40 the platform G on account of the greater friction on the horizontal portion of the platform causes the lower end of the cake to break up but in relatively large pieces. 45 The descent of the coke and thereby the manner in which it is broken up may be regulated as before described by the adjustable clamping action exerted on the coked cake by the guides D⁷. To increase the friction 50 between the guides and the coke the former may be roughened as indicated at D X in Fig. 4. When the coke from the retort being discharged has all been placed upon the coke receiving platform the carriage E is moved to the left, as is also the carriage F, which has preferably been coupled to the carriage E. The carriages E and F are then uncoupled and the clutches 55 are operated to release cover carriages D, and the left hand cover carriage D is moved

to the left to get it out of the road; at the same time the right hand cover carriage D is coupled to the carriage E as by the coupling connection D⁸. After the door B and carriage F are disengaged from the carriage E the latter is moved to the right to the quenching station located at the end of the battery, and the hoisting apparatus on the carriage F returns the door to the normal position where it is secured by the bolts B⁴. 70 If, as may be desirable to obtain the necessary clearance, the tracks D' do not extend beyond the end of the battery, the right hand cover D B will be disengaged from the carriage E when the former arrives at the end of the battery, and the coke carriage will then be moved on to the quenching station, where after the coke is quenched it is discharged either into the right hand car or the left hand car as desired by the chains H of the stationary hoisting mechanism, not shown, which engages the ears G¹¹ at the left or right hand edge respectively of the platform G. 80

Aprons or guides H² are provided for 90 insuring that the coke reaches the cars. When the guides H² are suitably perforated they serve as sieves permitting the coke breeze to drop through them. It will of course be understood that where there are more than one battery or unitary coke oven structures in a single plant, the hoisting and receiver tracks may be extended to permit the receiver and hoist to operate under all the batteries. The tracks for the covers may also be so extended though in case of such extension some modification would be necessary as otherwise the cover tracks would interfere with the operation of discharging between the batteries. It will be observed 95 that with the apparatus disclosed the various carriages can readily pass each other and that they can operate in either direction.

The discharging apparatus disclosed is highly advantageous in its general operation. All of the devices employed are located on one side beneath the furnace where their operation can be observed and controlled from a single point and by a single attendant. It will of course be understood that the various motors can be controlled from any one point, as from the carriage E, though no attempt to illustrate the controller connections has been thought necessary in view of the present state of the art of controlling motors from a distance. Because of these conditions the labor cost of discharging the furnaces is reduced to a minimum, the operator or operators work under favorable conditions and are not exposed to oppressive temperatures and the various devices are properly timed. 100 105 110 115 120 125

Certain novel features in the construction and arrangement of the coke receiver carriage, disclosed but not specifically claimed

herein, are specifically claimed in my co-pending application, Ser. No. 471,046, filed January 7, 1909, as a division of this application.

5 Having now described my invention, what I claim as new and desire to secure by Letters Patent is,

1. In combination with a coke oven having a vertical retort discharging through its lower end, a coke receiver movable under said retort to receive the coke as it is discharged from the retort, said receiver having its coke receiving surface extended in the direction of movement of the receiver to permit a movement of the latter under the retort while it is being discharged of a length several times greater than the dimension of the retort parallel to the direction of movement of the receiver, said surface being upwardly inclined at its forward end.

2. In combination with a coke oven having a vertical retort discharging from its lower end, a coke receiver movable under said retort to receive the coke as it is discharged from the retort, said coke receiver having its coke receiving surface extended in the direction of movement of the receiver to permit a movement of the latter under the retort while it is being discharged through a distance several times as long as the dimension of the retort parallel to such movement, and having the front and rear ends of said surface upwardly inclined.

3. In a coke oven structure having a vertical retort discharging through its lower ends, a coke receiver movable beneath the retort to receive coke from the retort and transport it to a discharge station, and a cover arranged to extend over the coke on the receiver during the discharging operation and to be bodily movable independently of the receiver and means for moving said cover with the receiver as the latter moves to carry the coke to the discharge station.

4. In combination with a coke oven structure, having a plurality of retorts which are emptied through their lower ends, and having a track for a coke receiving carriage running under the retorts, a coke receiving carriage running on said track, a second track parallel to the first, and a cover carriage running on said second track and movable with and above the coke receiver to protect the oven structure from the heat of the coke on the coke receiver.

5. In combination with a coke oven structure having a plurality of horizontally elongated retorts discharging through their lower ends, a receiver carriage movable transversely to the direction of the horizontal elongation of the retorts, and a pair of cover devices located above and movable in a direction parallel to that of the coke receiv-

ing carriage, means for causing said covers to have a relative movement to grip the coke between them with regulated pressure in discharging a retort, one of said covers being movable with said receiver when the latter having received a charge from one retort moves away to discharge the same.

6. In combination with a coke oven structure having retorts discharging from their lower ends and having a track for a pair of carriages running under the retorts, a coke receiver carriage running on one of said tracks, and a cover carriage running on the other of said tracks and movable to extend between the coke receiver and the oven structure, said cover carriage having depending aprons at its side edges whereby the coke on the receiver may be covered on top and at its sides by said cover.

7. In combination with a coke oven structure having a plurality of retorts discharging through their lower ends, a coke receiver moving transversely under each retort in the discharging operation and onto which the coke body projecting from the retort rests, a guide for taking the lateral thrust on the coke caused by the transverse movement of the receiver, and means for securing said guide in operative position at the side of each retort.

8. In combination with a coke oven structure having a plurality of retorts discharging from their lower ends, a coke receiver carriage beneath and movable transversely of said retorts during the discharging operation, an independently movable coke cover located between the coke receiver and the retorts and movable to cover the coke on the receiver, and means for coupling the coke receiver and the cover together for simultaneous movement.

9. In a coke oven structure having retorts discharging from their lower ends, a receiver movable under said retorts to receive the coke from each retort as the latter is discharged and to carry it away to a discharge station, and a coke cover located above the coke receiver and between it and the retorts and movable with said coke receiver toward the discharge station to limit the radiation of heat from the coke on the receiver, said cover having its face exposed to the coke formed of readily removable and relatively small units.

10. In combination with a coke oven structure having a plurality of retorts discharging through their lower ends, a pair of guides movable to positions beneath the various retorts, and means for moving said guides relative to each other in discharging each retort so that the coke discharged is gripped with a varying pressure and its descent is thereby regulated.

11. In combination with a coke oven

- structure having a plurality of retorts discharging through their lower ends, a pair of guides movable to positions beneath the various retorts, said guides having roughened coke engaging surfaces, and means for moving said guides relative to each other in discharging each retort so that the coke discharged is gripped with a varying pressure and its descent is thereby regulated.
10. 12. A discharging mechanism for a coke oven having a plurality of retorts arranged side by side and provided with a movable bottom wall for each retort which may be lowered to permit the retort to discharge through its lower end, said mechanism comprising in combination a coke receiver movable beneath and transversely of the retorts, means for lowering the bottom wall of the retort to be discharged to the level of the coke receiver, means for thereafter moving the coke receiver and the bottom wall transversely of the retort and means for causing the coke from said retort to be transferred by such movement from the bottom wall of 25 the retort onto the coke receiver.
13. A discharging mechanism for a coke oven having a plurality of retorts arranged side by side and provided with a movable bottom wall for each retort which may be lowered to the proper level relative to the coke receiver so that the coke may be transferred from the bottom wall to the receiver in an even and regular manner, said mechanism comprising in combination a coke receiver movable beneath and transversely of the retorts, means for lowering the bottom wall of the retort to be discharged, means for thereafter moving the coke receiver and the lowered bottom wall transversely of the retort, and means engaging the coke above the top of the bottom wall when the latter is lowered and arranged to prevent the movement of the portion of the coke engaged in a direction parallel to the movement of the receiver.
14. A discharging mechanism for a coke oven having a plurality of retorts arranged side by side and each provided with a movable bottom wall to permit the retort to discharge from its lower end, said mechanism comprising in combination a coke receiver carrier movable beneath and transversely of each retort as the latter is being discharged, mechanism for dropping the bottom wall of each retort onto said coke receiver at the beginning of the discharging operation, and means for causing the coke from said retort to be transferred by the transverse movement of the carrier from the bottom wall of the retort onto the said receiver.
15. In combination with a coke oven structure provided with a plurality of retorts each having a movable bottom wall, a coke receiver moving under and transversely of each retort as the latter is being discharged, and mechanism for dropping the bottom wall of each retort onto the said coke receiver at the beginning of the discharging operation said receiver having the forward end of its receiving platform upwardly inclined to the approximate level of the upper surface of said bottom wall when the latter is lowered, whereby as the receiver moves transversely the coke is transferred from the bottom wall on to the receiver without due jarring.
16. In combination with a coke oven structure having a plurality of retorts, each provided with a movable bottom wall, a coke receiver beneath the retorts and movable transversely of each retort as the latter is discharged, an independently movable hoisting device for raising and lowering the bottom walls, and means for coupling the hoist to the receiver during the discharging operation.
17. In combination with a coke oven structure having a plurality of horizontal elongated coking retorts arranged side by side and provided each with a movable bottom wall, a track beneath the retorts, and extending transversely to the direction in which the retorts are horizontally elongated, a coke receiving carriage on said track and extending beneath the ovens means for lowering the bottom wall of each retort in discharging the same to bring the bottom edge of the coke at the proper level with respect to the coke receiver, whereby when the coke receiver moving on said track is thereafter caused to traverse said retort the coke is discharged on it, and means for regulating the descent of the coke during the discharging operation.
18. In combination with a coke oven structure having a plurality of horizontally elongated and deep coking retorts arranged side by side and provided each with a movable bottom wall, a track beneath the retorts and extending transversely to the direction in which the retorts are horizontally elongated, a coke receiving carriage on said track, means for moving the bottom wall of each retort in discharging the same to thereby bring the bottom edge of the coke at the proper level with respect to the coke receiver, whereby when the coke receiver moving on said track is caused to traverse the coke is discharged on it, and means for regulating the descent of the coke, said means comprising clamping guides at opposite sides of the retort and relatively movable with respect to each other.
19. In combination with a coke oven structure having a plurality of vertical retorts and a movable bottom wall for each retort and apparatus for discharging said retorts, said apparatus including a device movable

into positions beneath the various retorts for lowering each retort bottom wall in discharging that retort with the coke resting on it, receiving means for receiving the coke from the bottom wall when it is so lowered, and means for moving said receiving means and the lowered bottom wall of the retort

to be discharged transversely of the retort to cause the coke resting on said bottom wall to be transverse to said receiving means.
